CLAIM

The ornamental design for flash memory storage device, as shown and described.

DESCRIPTION

FIG. 1 is a perspective view of a flash memory storage device showing my design in a first configuration;

FIG. 2 is a first perspective view showing my design in a second configuration;

FIG. 3 is a second perspective view of the second configuration;

FIG. 4 is a perspective view showing my design in a third configuration;

FIG. 5 is a top view of the first configuration;

FIG. 6 is a bottom view of the first configuration;

FIG. 7 is a side view of the first configuration, left and right side views being mirror images to each other;

FIG. 8 is a front view of the first configuration; and,

FIG. 9 is a rear view of the first configuration.
